UNITED STATES PATENT OFFICE.

FRANK G. MURPHY, OF MASON CITY, IOWA.

DESIGN FOR AN EYEGLASS LENS.

Application filed February 13, 1923. Serial No. 5,164. Term of patent 14 years.

To all whom it may concern:

Be it known that I, FRANK G. MURPHY, a citizen of the United States, and a resident of Mason City, in the county of Cerro Gordo and State of Iowa, have invented a certain new, original, and ornamental Design for an Eyeglass Lens, of which the following is a specification, reference being had to the accompanying drawing, forming part thereof.

Figure 1 shows a front elevation of an eye glass lens showing my new design; and

Figure 2 shows a sectional view on the line 2—2 of Figure 1.

I claim:

The ornamental design for eyeglass lens as shown.

Des Moines, Iowa, February 1, 1923.
